STABLE DRY OXIDIZING MIXTURE HAVING
CONTROLLED OXYGEN EVOLUTION RATE
WHEN USED IN SOLUTIONJoseph L. Richmond, Woodstown, N. J., assignor
to E. I. du Pont de Nemours & Company, Wil-
mington, Del., a corporation of DelawareNo Drawing. Application June 16, 1939,
Serial No. 279,391

4 Claims. (Cl. 252—186)

This invention relates to a stable oxidizing mixture having a regulated rate of oxygen evolution. More particularly it relates to a dry mixture comprising a per-salt as the principal ingredient together with a wetting agent, a stabilizing agent and an oxygen evolution accelerating agent.

This case is a continuation-in-part of applicant's copending application Serial No. 229,675, filed September 13, 1938.

Many oxidizing materials are known, but nearly all of them have distinct disadvantages. One of the most serious disadvantages of such materials is a tendency to deteriorate upon standing. This tendency is present, for example, in hydrogen peroxide and in sodium perborate, two well known oxidizing agents. Another disadvantage is that stabilized oxidizing materials will not evolve their oxygen at a rate which is satisfactory in textile operations and likewise will not evolve all the active oxygen contained in the product, thereby cutting down the effective strength of the agent. The textile industry, in particular, evidences a need for an oxidizing agent for vat dyestuffs which agent will not deteriorate upon standing, which is stable to iron so that it can be used in iron equipment and which evolves all of its oxygen at the optimum rate for textile operations.

This invention has as an object the preparation of an improved oxidizing agent. Another object is the provision of a stable, solid oxidizing material for use in the textile industry. A further object is to provide an improved oxidizing agent wherein sodium perborate is the principal ingredient. Another object is the preparation of a stable oxidizing agent which will develop its oxidizing power to a maximum at a definite rate. Other objects will appear herein-after.

These objects have been accomplished by the following invention; a solid stable oxidizing mixture comprising a per-salt, for example, sodium perborate, as the principal ingredient mixed with a wetting agent, for example, sodium lauryl sulfate, a stabilizing agent, for example, sodium pyrophosphate and an oxygen evolution accelerating agent, for example sodium sulfate.

The oxidizing compositions of the present invention are compounded by mixing the finely divided ingredients together in the dry solid state until an intimate mixture is obtained, any suitable mixing apparatus being used.

The invention is illustrated by the following 55

specific examples wherein the parts stated are by weight.

Example 1

5 Five hundred fifty six parts of sodium perborate monohydrate, 37 parts of sodium pyrophosphate, 333 parts of anhydrous sodium sulfate and 74 parts of the sodium salts of a mixture of coconut oil fatty alcohol sulfates are intimately mixed in a suitable apparatus. A dry stable product containing 8.5% available oxygen is obtained.

Example 2

15 Eight hundred fifty six parts of sodium perborate tetrahydrate, 37 parts of sodium pyrophosphate, 33 parts of anhydrous sodium sulfate and 74 parts of the sodium salts of a mixture of coconut oil fatty alcohol sulfates are intimately mixed in a suitable apparatus. A dry stable product containing about 8.5% available oxygen is obtained.

20 In order to test the oxidizing effect of the compositions made in Examples 1 and 2 the following procedure was carried out. A solution 25 of each of the above two mixtures was prepared containing 0.026% available oxygen. The solutions were heated at 140° F. The loss of available oxygen was determined at regular intervals by withdrawing aliquot portions and titrating the 30 residual available oxygen with standard potassium permanganate solution. The results are contained in the following table:

Table I

35	Time, minutes	Percent of available oxygen liberated	
		Example 1	Example 2
40	10.....	62	40
	20.....	91	72
	30.....	96	88
	60.....	98	96
	90.....	100	97

45 As may be readily seen from the above table, with the other three ingredients held constant, an increase in the percentage of anhydrous sodium sulfate in the dry mix results in an increase in the rate of oxygen evolution from the composition in solution.

50 The oxidizing effect of the products of the above examples was also tested on dyeings of vat dyestuffs and the said products were found to be superior to sodium perborate, weight for weight.

In order to more fully illustrate the effect of

variation of the composition, the following examples are set forth in tabular form:

Example	Parts of sodium perborate monohydrate	Parts of sodium pyrophosphate anhydrous	Parts of sodium sulfate anhydrous	Parts of wetting agent*
III	3000	1000	1020	380
IV	3000	500	1520	380
V	3000	400	1620	380
VI	3000	300	1720	380
VII	3000	200	1820	380
VIII	3000	100	1920	380
IX	3000			
X	3000	2000		
XI	3000	2000	20	380
XII	3000		20	380
XIII	3000		2000	

*"Wetting agent" in the above examples signifies the sodium salts of a mixture of coconut oil fatty alcohol sulfates.

The rate of liberation of available oxygen from the mixtures of Examples III to XIII tested as above described are set forth in Tables IIA and IIB.

Table IIA

Time, minutes	Percent of available oxygen liberated					
	Ex. III	Ex. IV	Ex. V	Ex. VI	Ex. VII	Ex. VIII
30	15.4	23.1	19.2	26.9	42.3	65.4
60	23.1	38.5	42.3	46.1	69.2	88.4
90	34.6	42.3	57.7	65.4	80.8	96.2

Table IIA clearly shows that the invention may be practiced with wide variations in the composition in the mixture with resulting variations in the rate of oxygen liberation. Since various uses of the oxidized compositions will require different rates of oxygen evolution in order to maintain maximum efficiencies in the various operations involved, it is highly important that the rate of evolution of oxygen be adjustable to take care of the particular situation. This flexibility is considered one of the most important features in the present invention.

Table IIB

Time, minutes	Percent of available oxygen liberated				
	Ex. IX	Ex. X	Ex. XI	Ex. XII	Ex. XIII
30	38.5	3.8	19.2	61.6	84.6
60	92.3	7.7	30.8	92.4	100.0
90	100.0	11.5	50.0	96.2	-----

The results in Table IIB show a number of important facts. It is known that sodium perborate deteriorates on standing and sodium pyrophosphate is added to stabilize the sodium perborate. A comparison of the rate of liberation of oxygen in Example IX and Example X shows that sodium pyrophosphate not only stabilizes the dry sodium perborate but also materially retards oxygen liberation in solution. Example XI shows that even a very small amount of sodium sulfate has a marked effect on increasing this oxygen liberation rate. As shown in Example XII the omission of sodium pyrophosphate and addition of a very small amount of sodium sulfate greatly increases the initial rate of oxygen liberation thereby giving a much more uniform liberation rate. Example XIII shows that larger amounts of sodium sulfate increase the liberation of oxygen to a rate far in excess of that obtained with sodium perborate alone.

Among the per-salts suitable for the mixtures of the present invention, there may be mentioned by way of example, sodium percarbonate, sodium perphosphate, sodium or ammonium per-sulfate, etc. The preferred per-salt is sodium perborate, which may be used as either the monohydrate or as the tetrahydrate, the water of crystallization being inert in the mixture. Suitable adjustment of parts must be made if the tetrahydrate is used instead of the monohydrate to provide the same percentage of available oxygen in the mixture.

The preferred stabilizing agent is sodium pyrophosphate. The preferred oxygen-evolution-accelerating agent is sodium sulfate.

Sec.-pentadecyl sodium sulfate, cetyl betaine, alkylated naphthalene sulfonate, paraffin sulfonic acid and Turkey red oil are mentioned as examples of wetting agents which may be used in the novel mixture. The preferred wetting agents, however, are the salts of higher aliphatic alcohol sulfates having 8 to 18 carbon atoms in the alkyl radical. As examples of such compounds, mention is made of secondary-hexadecyl, secondary-heptadecyl and secondary-pentadecyl sodium or ammonium sulfates, sodium oleyl sulfate, pentadecyl-8-sodium sulfate, etc. The wetting agent ingredient of the novel mixture may be one of the wetting agents used alone or in mixture of one with another or others. Especially preferred as the wetting agent ingredient is sodium lorol sulfate. This is a mixture of the sodium salts of coconut oil fatty alcohol sulfates made by catalytically hydrogenating coconut oil to produce the corresponding alcohols (known to the trade as Lorol) and sulfating by known methods. Lorol is a mixture of saturated fatty alcohols of from ten to eighteen carbon atoms. The mixture contains about fifty percent of dodecyl alcohol.

The novel oxidizing mixture of the invention must have the oxidizing agent as the principal ingredient. Using the preferred ingredients as examples, the preferred proportions of ingredients are sodium perborate calculated as the monohydrate ($NaBO_3 \cdot H_2O$) in the amount of 40% to 90%, sodium lorol sulfate in the amount of 5% to 10%, sodium pyrophosphate in an amount of 3% to 40% and sodium sulfate in an amount of 0.37% to 40%.

Although no theoretical explanation is known to the applicant, according to the present invention, the addition of small amounts of a wetting agent, a stabilizing agent and an oxygen-evolution-accelerating agent to a per-salt produces an oxidizing mixture superior to its chemical effect on vat dyeings and superior in its keeping qualities over the per-salt alone. Not only are such mixtures free of deterioration on standing, but also they are not sensitive to iron, and, hence can be used in the iron equipment usually employed in oxidizing vat colors. By using the proper proportions of stabilizing agent and the oxygen-evolution-accelerating agent, the rate and extent of evolution of oxygen from the per-salt is adjusted so that when used in a textile operation, maximum efficiency is obtained.

It has been found desirable to so regulate the oxidizing mixture that it contains about 8.5% available oxygen and this is a preferred embodiment of the invention.

While for the purpose of treating fabrics in dyeing processes it is desirable to have a wetting agent present to assist in bringing the solution made from the oxidizing mixture into contact

with the fabric, the wetting agent is not believed to materially affect the rate of oxygen evolution, and, hence, it may be omitted from the mixture where this function is unnecessary.

The stabilizer is of primary importance in improving the keeping qualities of the dry mixture. Where there is no storage period contemplated and where an oxidizing agent having a high rate of oxygen liberation is desired the stabilizer may be omitted. A mixture of per-salt and sodium sulfate gives a higher rate of oxygen liberation than is obtained by the per-salt alone, and this is a feature of the present invention. Under these circumstances the ingredients may be mixed directly in solution.

This invention has the advantage that the oxidizing composition is stable, thus reducing need for rapid turnover. Its oxygen-evolution-rate is controlled, assuring a substantially constant oxidizing power. It may be used without testing for strength and changing of formulae from day to day. The composition is a dry solid, soluble in water, permitting easy handling and weighing. The stability of the mixture to iron permits its use in iron equipment and also the presence of iron impurities in the ingredients. Being a dry mechanical mixture, the new oxidizing composition is easily and cheaply prepared.

It is to be understood that the invention is not limited to the specific embodiments herein described, the proper limits being defined by the scope of the appended claims.

I claim:

1. An oxidizing composition, which is a mixture of dry materials, comprising sodium perborate as the principal ingredient, a wetting agent, sodium pyrophosphate as a stabilizing agent and normal sodium sulfate as an oxygen-evolution-accelerating agent.
2. An oxidizing composition, which is a mixture of dry materials, comprising sodium perborate as the principal ingredient, a water soluble salt of a higher aliphatic alcohol sulfate, sodium pyrophosphate as a stabilizing agent and normal sodium sulfate as an oxygen-evolution-accelerating agent.
- 15 3. An oxidizing composition having about 8.5% available oxygen, which is a mixture of dry materials, comprising sodium perborate as the principal ingredient, a water soluble salt of an alkyl sulfate, the alkyl radical containing 8 to 18 carbon atoms, sodium pyrophosphate and normal sodium sulfate as an oxygen-evolution-accelerating agent.
- 20 4. An oxidizing composition, which is a mixture of dry materials, comprising 40% to 90% sodium perborate, 5% to 10% of the sodium salts of a mixture of coconut oil fatty alcohol sulfates, from 3% to 40% sodium pyrophosphate and from 0.37% to 40% normal sodium sulfate as an oxygen-evolution-accelerating agent.

JOSEPH L. RICHMOND.
